UNITED STATES PATENT OFFICE

2,335,013

FRUIT KNIFE

Samuel C. Kennett, Helena, Mont.

Application April 27, 1943, Serial No. 484,757

2 Claims. (Cl. 30—24)

The present invention relates to new and useful improvements in kitchen tools and more particularly to a fruit knife designed for easily and effectively removing the non-edible web or partition from grapefruit.

An important object of the invention is to provide a double-edged tool of this character, either edge of which may be used for cutting purposes and which, at the same time, is neat and attractive in appearance, strong and durable and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which—

Figure 1 is a plan view showing the tool in use.

Figure 2 is a side elevational view.

Figure 3 is a top plan view of the tool with the blades separated for convenient cleaning.

Figure 4 is an end elevational view.

Figures 5 and 6 are sectional views taken respectively on the lines 5—5 and 6—6 of Figure 2, and

Figure 7 is an enlarged fragmentary plan view of the tubular head of the tool.

Referring now to the drawings in detail the numeral 5 designates a blade of spring steel or other suitable material capable of holding a cutting edge, and of uniform width and having one end secured in a wooden or other suitable handle 6.

The blade is bent upon itself intermediate its ends and its bent portion is formed into a substantially tubular head 7.

The free end of the blade extends inwardly toward the handle in parallelism to the blade 5 and forms a second blade 8. The blade 5 is formed adjacent the handle with an offset 9 to space the blades 5 and 8 apart.

A slide 10 is slidably mounted on the blade 5 between the offset 9 and the handle to engage the inner end of the blade 8 to secure the same against spreading movement. A protuberance 11 is formed on the side of the blade 5 adjacent the handle to limit movement of the slide.

The side edges of the blades 5 and 8, as well as the head 7, are beveled to provide cutting edges

and the outer edges of the head 7 are formed with beveled notches 12 and 13 to center the web or partition 14 of a grapefruit 15 between the blades during the cutting thereof in a manner indicated in Figure 1 to sever the pulp from the web at each side of the latter simultaneously and thus remove the web from the grapefruit.

The relatively wide head 7 facilitates the severance of the web at the point where it joins the rind and the rounded formation of the head 7 at its junction with the blades 5 and 8 tend to ease the web into the more contracted space between the knife blades.

By sliding the slide 10 rearwardly the blade 8 may be released and spread apart to facilitate cleaning of the tool.

It is believed the details of construction, operation and manner of use of the device will be readily understood from the foregoing without further detailed explanation.

Having described the invention, what is claimed as new is:

1. A grapefruit tool adapted for removing the non-edible web separating the pulp segments and comprising a blade having a handle at one end, said blade being bent intermediate its ends upon itself, a tubular head at the bent portion of the blade and defining a second blade disposed parallel to the first blade, means connecting the free end of the second blade to the first blade, both of said blades being beveled along their longitudinal edges to form knives adapted to sever the pulp of a grapefruit at opposite sides of its web, and a notch at the outer edge of the tubular head, said notch having sharpened edges.

2. A grapefruit tool adapted for removing the non-edible web separating the pulp segments and comprising a blade having a handle at one end, said blade being bent intermediate its ends upon itself, a tubular head at the bent portion of the blade and defining a second blade disposed parallel to the first blade, an offset in said first blade adjacent the handle and spacing the blades apart, means connecting the free end of the second blade to the first blade inwardly of the offset, both of said blades being beveled along their longitudinal edges to form knives adapted to sever the pulp of a grapefruit at opposite sides of its web, and a notch at the outer edge of the tubular head, said notch having sharpened edges.

SAMUEL C. KENNELL.
